AWNING

Theodore J. Bottom, Kirkwood, Mo. (% Aluma Kraft Manufacturing Co., 1330 N. Rock Hill Road, St. Louis, Mo.)

Filed Jan. 4, 1960, Ser. No. 58,914

Term of patent 14 years

(Cl. D21—6)

Fig. 1 is a perspective view showing my new design for an awning;

Fig. 2 is a perspective view thereof from the end opposite to that shown in Fig. 1; and

Fig. 3 is an enlarged view, partly in cross section as seen along line 3—3 of Fig. 1, illustrating the configuration of the roof panels and the interior of the side panels.

I claim:

The ornamental design for an awning, substantially as shown and described.
